UNITED STATES PATENT OFFICE.

JOSEPH J. LANZIT, OF LOS ANGELES, CALIFORNIA, ASSIGNOR, BY MESNE ASSIGNMENTS, TO NATIONAL PAPER PRODUCTS COMPANY, OF SAN FRANCISCO, CALIFORNIA, A CORPORATION OF CALIFORNIA.

PAPER PAIL.

Application filed March 2, 1921. Serial No. 449,083.

To all whom it may concern:

Be it known that I, JOSEPH J. LANZIT, a citizen of the United States, residing at Los Angeles, in the county of Los Angeles and 5 State of California, have invented new and useful Improvements in Paper Pails, of which the following is a specification.

This invention relates to paper pails, and has for its object the provision of improved 10 closure means for the same which may be readily fastened.

The invention will be readily understood from the following description of the accompanying drawings, in which—

15 Figure 1 is a plan view of the blank from which the pail is folded.

Fig. 2 is a perspective view of the pail formed from the blank and showing the closure flaps before engaged in fastening 20 position.

25 Fig. 3 is a similar view showing the closure flaps engaged in fastening position.

Fig. 4 is a fragmentary perspective view showing a modified form of the retaining 30 strip secured to one of the closure flaps.

The blank from which the pail is formed may be of usual construction including bottom 1, side walls 2 and corner members 3 between adjacent side walls and adapted, 35 when the side walls are folded upwardly, to be folded over the outside of an opposite pair of side walls, as clearly shown in Fig. 2.

40 A usual handle wire 4 is inserted through the overlapping ends of these corner pieces and through the side walls for retaining the parts in folded position.

45 The upper edges of the side walls are provided with extensions 5 forming closure flaps for the pail. One pair of opposite closure flaps are bent along lines 6 at the upper edges of the side walls so as to overlie one another in order to form closure means.

50 Of the other pair of opposite closure flaps, one of the same is also bent along line 6, while the opposite closure flap has a tongue 7 cut from the middle portion thereof and projecting beyond the side wall. The flap surrounding the tongue is bent along line 6, but the tongue forms a continuation of the side wall with no bend provided at the upper edge of the latter.

55 When closing the pail, the first mentioned pair of flaps are bent over one another, as

shown in Fig. 2, and the flap having the tongue 7 cut therefrom is then bent downwardly upon the first pair of closure flaps so as to leave tongue 7 projecting upwardly. This tongue is provided with an opening 8 and the opposite closure flap is provided 60 with a retaining means adapted to engage said opening and shown as a strip 9 of readily bendable material secured to the flap and projecting beyond the same. After the flap having the tongue formed therein has 65 been bent to closed position, the opposite flap carrying strip 9 is bent downwardly with the strip received in opening 8. The parts are so arranged that when the flap carrying strip 9 has been bent all the way 70 down with the strip 9 through the opening 8, the tongue 7 will be drawn inwardly and downwardly so as to bend the same along the line of the upper edge of the side wall, when the strip 9 projecting through opening 8 is reversely bent upon the flap carrying the same so as to fasten the flaps in 75 closed position.

By providing the upwardly projecting tongue adapted to be engaged by a projecting strip of the opposite closure flap, the pair of closure flaps may be readily engaged, and when secured together with the tongue bent downwardly will form positive fastening means for the closure flaps of the 80 pail.

85 In the modification of the invention illustrated in Fig. 4, the strip carried by one of the closure flaps 5 and adapted to be received in opening 8 is shown as an extension 90 9^a of the flap provided with side portions 12 adapted to be bent down upon extension 9^a so that the latter may be readily projected through opening 8. The extension is then folded back upon itself and the side 95 flaps 12 are unfolded so as to form a locking tongue which will be held in locked position extending through opening 8. The outer end of extension 9^a may be tapered as shown at 13 and the outer ends of side portions 12 oppositely inclined as shown at 14, so that when the side portions 12 are folded upon the extension, the tongue will have a tapering end which may be readily projected through opening 8.

100 105 Various changes may be made without departing from the spirit of the invention as claimed.

What is claimed is:

1. A pail folded from a blank forming a bottom, four sides and folded corner pieces, opposite extension closure flaps bent to overlap one another and opposite flaps adapted to be pulled down and overlapped, a tongue cut from one of the last mentioned flaps and extending to the side wall of the pail and having a perforation, and a strip secured to the other one of the last closure flaps and adapted to pass under the tongue and upwardly through the opening and be bent over the tongue.
2. A pail folded from a blank forming a bottom, four sides, and folded corner pieces,

closure flaps bent to overlie one another, opposite flaps adapted to be pulled down and overlapped, a tongue cut from one of the last mentioned flaps forming an extension of one of the sides adapted to be folded at its lower end and having a perforation therein, and a strip secured to one of the flaps and adapted to project through the said perforation and lock the tongue in folded position when bent back upon itself, whereby the closure flaps may be folded one at a time.

In testimony whereof I have signed my name to this specification.

JOSEPH J. LANZIT.
